DISPLAY CASE

Victor Lebow, Brooklyn, N. Y., assignor to Chester H. Roth Co., Inc., New York, N. Y., a corporation of New York

Application September 10, 1948, Serial No. 148,540

Term of patent 7 years

(Cl. D80—11)

To all whom it may concern:

Be it known that I, Victor Lebow, a citizen of the United States of America, residing at Brooklyn, in the county of Kings and State of New York, have invented a new, original, and ornamental Design for a Display Case, of which the following is a specification, reference being had to the accompanying drawing, forming part thereof.

In the drawing:

Fig. 1 is a front elevational view of a display case showing my new design;

Fig. 2 is a vertical sectional view taken along lines 2—2 of Fig. 1.

I claim:

The ornamental design for a display case, substantially as shown.

VICTOR LEBOW.
